LIQUID COOLING APPARATUS

Joseph Jacir, Neuilly-Plaisance, France

Application June 22, 1949, Serial No. 100,650
In France June 29, 1948

1 Claim. (Cl. 261—30)

2

A number of types of liquid coolers are known, which operate by a combination of convection and evaporation, with heat exchange having a fluid circulated in counter-current by natural or forced draught.

The various existing apparatus have certain disadvantages namely large overall dimensions, liability to become obstructed, or again too high a pumping or blowing power or untimely entrainment of water.

The object of the present invention is to provide a type of apparatus in which the disadvantages hitherto encountered are avoided.

In this apparatus, the liquid arriving at the top is divided by means of distributors into droplets or fine streams, and these droplets or fine streams of liquid are collected by means of a receiving system after having fallen a predetermined height.

An important feature of the invention resides in the provision of an arrangement for rendering uniform the flow of water, this arrangement consisting essentially in providing at the bottom of the distributor a series of teeth or vertical or inclined points, the extremities of which are downwardly directed, and which are intended to divide the fluid sheet into thin streams flowing continuously or drop by drop on to the receiving arrangement.

In the present form of embodiment of the invention, the distributor comprises parallel series of steps staggered in height and in width in the manner of a flight of stairs, which permit the water to spread transversely, each of the lower steps being provided with the aforesaid arrangement.

The receiving arrangement is composed of separate parallel elements having suitably curved water-collecting surfaces which direct the water towards collecting troughs, the said elements being so disposed that the air can circulate vertically between the troughs and the collecting surfaces to cool the thin streams of water overflowing from the distributing arrangement.

The invention is also characterised by other forms of distributors, in which the distribution of the liquid is effected by flow from an overflow of any form on to a corrugated plate, the pitch of which corresponds to the spacing of the points or elements to be fed, the depth of each corrugation being calculated as a function of the delivery required at each of the points fed. It is possible to obtain at each of these channels a thin stream of liquid of the desired form, i. e. a circular jet or film.

The invention will now be described with ref-

erence to the accompanying drawings, which show by way of example various constructional forms of cooling apparatus according to the invention, and in which:

5 Figure 1 shows in perspective a distributing arrangement.

Figure 2 is a variant of the arrangement shown in Fig. 1.

Figure 3 is a sectional view of a receiving arrangement.

10 Figure 4 is a sectional view of a variant of the receiving arrangement.

Figures 5 and 6 are elevational side and face views of a whole distributing arrangement.

15 As has already been stated, the cooling apparatus (Fig. 1) comprises in particular a distributing arrangement and a receiving arrangement. The water distributor is constituted by an element or a series of elements, each of which com-

20 prises a number of staggered steps 1, on which the water spreads. After having spread sufficiently, the water reaches an element comprising one or more series of vertically disposed teeth 2.

25 These distributors may be formed in different ways. For example they may be formed, as shown in Figure 1, of separate elements constituted by tubes of rectangular section, or of plates bent in L-form. Another simple form of embodiment consists in stamping a thin sheet of

30 metal comprising both the steps and the teeth (Figure 2). The advantage of the latter method is that the weight involved may be extremely small if very thin sheet metal is employed. It is also possible to employ stainless sheet metal,

35 which would be too costly in another apparatus.

The said distributors are disposed parallel and in juxtaposition to one another, so that the whole water-fall coming or overflowing from a receptacle situated above them falls on to one 40 of the elements. To this end, an inclined part may be provided at the top of the distributor, as shown in Figure 2, to receive the water coming from an upper receptacle and to direct it towards the steps.

45 The liquid-receiving system may be designed in two ways:

A first simple method consisting in disposing thin elements 3 having parallel inclined surfaces, each of which overhangs, or dips into, a liquid-collecting trough 4 situated in the lower part.

50 The various elements of the distributing and receiving arrangements are so disposed that any droplet or thin stream of liquid first encounters in its vertical fall a distributing element, and then a receiving element, and that the current

emanating from a fan or the like encounters minimum impedance in its upward movement. This upward movement may be assisted by straightening of the upper part of the element 3.

A modification of the receiving arrangement consists in employing troughs 5 disposed in steps and staggered so that the aforesaid conditions are also fulfilled (Fig. 4).

The whole of an apparatus according to the invention may be constituted in the following manner (Figures 5 and 6):

A tank 6 comprises at the top a cistern 7, to which the water is delivered. Extending from this cistern are horizontal tubes 8, which distribute the water to the troughs 9.

The water falls from the said troughs 9 by overflowing or by any other means on to the distributors 1 disposed perpendicularly to the troughs.

The water is then collected by water receivers each composed of an oblique straightened metal sheet 3 and of a trough 4.

The troughs 4 discharge the water into a lateral collector 13 having an outlet orifice 14.

The air forced by a motor-fan unit 15 passes horizontally in counter-current, into a shell or sleeve 16; it is rectified by the blades 17 and is discharged through the top of the apparatus.

I claim:

In a liquid cooling apparatus, in combination, an upper receptacle adapted to receive liquid from a source thereof, a horizontal row of parallel troughs supplied by gravity from said upper receptacle, the troughs having horizontal edges over which the liquid over-flows from the troughs

in the form of a thin sheet, a plurality of horizontal surfaces arranged in stepped relationship and extending at right angles to the said edges of the troughs, the lowermost element of each of said stepped surfaces being in the form of a substantially vertical wall, the lower horizontal edge of which is serrated whereby the liquid moving downwardly over said vertical wall flows to the apex of each serration and falls freely therefrom as a droplet, a plurality of lower receptacles disposed below said stepped surfaces for reception of said droplets, and means providing upwardly flowing cooling air currents through which said droplets freely fall in passing from said serrations to said lower receptacles.

JOSEPH JACIR.
